CENTRIFUGING APPARATUS

William F. Wells, Cambridge, Mass.

Application October 22, 1932, Serial No. 639,121

2 Claims. (Cl. 233—12)

This invention relates to centrifuging apparatus and is particularly devised for the purpose of aiding in the analysis of air or other gaseous bodies for the purpose of obtaining a quantitative analysis of the bacterial content of such air or gas.

Generally speaking, the invention embraces a centrifuging apparatus having a central air intake tube around which is revolved a tubular receptacle containing a collecting medium, such for example as a cultural medium, which if in a fluid state, under the action of centrifugal force, builds up into a thin film on the inside wall of the tubular receptacle and over which the air admitted by the intake tube passes to the outlet, the bacterial or similar solid particles being centrifugally expelled from the column of air against the interior surface of the container lining before the air escapes. For convenience, the circulation of air through the intake tube and through the film receptacle is effected by providing the revolving outlet head with projecting vanes which act as a centrifugal fan or pump to draw the air through the intake tube and the film receptacle.

These and other features of the invention will be particularly described in the following specification and will be defined in claims annexed.

In the accompanying drawing I have illustrated a simple and convenient apparatus embodying the principles of this invention, in which

Fig. 1 is a vertical central section of the centrifuging apparatus connected at its bottom with a rotating motor or driving means.

Fig. 2 is a plan view, partly in section, on the section-indicating lines 2—2 of Fig. 1.

In the practice of this invention according to the specific form illustrated in the drawing, I provide a base ring 1 having at its rear a vertical socket 1^a for the reception of an upright rod or standard 2, on which is mounted a projecting supporting bracket 3 which is adjustably mountable at different levels on the standard 2 by means of the supporting nut 4, which carries a set screw 45 for clamping it to any desired elevation on the standard.

The air tube bracket 3 at its outer end is provided with a central vertical bore coaxially aligned with the driving shaft 16 of the underneath motor. The bracket is split at its outer end, as shown at 3^a, and in the bore is inserted a gasket or bushing 5 of compressible material which firmly grips the exterior of an inserted air intake tube 6, the jaws 3^a being clamped tightly by 55 means of the clamping screw 3^b. On the top of

the air intake tube or duct 6 is mounted a calibrating intake nozzle 7, that is, a nozzle whose central bore or passage is dimensioned to admit a predetermined quantity of air at uniform speed of rotation of the apparatus that is definitely known, so that the quantity of air passing through the intake at the normal speed of the apparatus in a given unit of time is definitely measured, since in bacterial analysis it is in most cases desirable to know the volume of air analyzed as well as 10 the bacterial count.

A short distance below the suspension bracket 3 is secured around the intake tube 6 a bearing supporting collar 8, which carries a self-aligning anti-friction bearing 10 which fits into the 15 upper end of the centrifuge head 9 and is protected by a circular cover 11 secured to the upper end of the head.

The revolving head comprises upper and lower annular members 9, 9^b having, respectively, radially projecting annular flanges 9^a and 9^c which are integrally united by means of vertical webs 9^d which form the vanes or wings that act as a centrifugal fan to expel the air from the interior of the head, which is supplied to it from 25 the intake tube 6. The head 9 is also provided with an inner hub or spider 9^e centrally bored to receive a tube 12, which is concentric with the air intake tube 6, which latter projects through to the lower end of the tube 12 and has a flared discharge end as shown at 6^a to nearly close the lower end of the tube 12 without actually coming in contact therewith inasmuch as the tube 12 rotates with the head, while the tube 6 is fixed or stationary.

Fitted inside the lower member 9^b of the centrifuge head is an outside tubular member 13, which forms a hollow drive shaft connection for rotating the centrifuge. There is sufficient annular space between the tube 12 and the hollow 40 shaft 13 to permit the insertion of a receptacle or test tube 20 which carries in its bottom a small supply of fluid which in bacterial analysis has the character of a cultural medium.

In its lower end the tubular casing or shaft 13 is releasably attached by means of clamping screws 15 to the driving head 14, which is itself secured to the projecting upper end of the spindle 16 of a driving motor M, which may be mechanically or electrically driven according to circumstances. In a recess formed in the top of the driving head 14 is secured an elastic cushion or pad 19 upon which the test tube or receptacle 20 rests.

By releasing the clamping screws 15 carried by the head 14 the centrifuge may be raised on the 55

standard 2 sufficiently to permit the insertion of a test tube containing the fluid cultural medium with the bottom of the test tube resting on the cushion of pad 19. The test tube externally is 5 very near the internal diameter of the casing or shaft 13, but need not ordinarily be attached thereto. After the insertion of the test tube the casing or shaft 13 is again coupled or clamped to the driving head 14 and upon the starting of the 10 motor the fluid in the bottom of the receptacle under the influence of centrifugal force builds up into an annular film on the inside of the wall of the receptacle, as indicated in dotted lines, thus exposing a hollow annular film to contact with 15 the air which, by means of the fan vanes 9^d, is drawn down through the calibrating nozzle 7 and thence upwardly between the tube 12 and the film of liquid until it escapes through the openings between the vanes. By reason of the revolution 20 of the film itself on the outside of the column of air and of the tube 12 bounding the inside of the column of air, the column of air is also revolved as it moves upward and, owing to centrifugal force, the minute solid particles, such 25 as bacteria or the like, are expelled against the liquid film to which they adhere and which acts as a carrier for the accumulation of these minute bodies which it collects.

It will therefore be seen that the revolving of 30 the centrifuge at normal speed not only builds up through centrifugal force an annular film of liquid, but also draws in at a constant rate a known or ascertainable quantity of air from which the bacteria are expelled against the surrounding film 35 which retains them for cultural development and counting.

The bracket 3 is splined to the rod 2, as shown at 3^c, in order to prevent rotative displacement while permitting the bracket to slide upward for 40 the insertion or removal of the test tube from the centrifuge.

While I have described the above apparatus as effective for the purpose of separating bacteria from a body of air, nevertheless it will be understood 45 that I do not confine myself to the use of the apparatus for such purpose, although it will be found that an apparatus built according to the above described principles is very effective in carrying out this new method of bacterial analysis 50 of air of which I am the inventor and which forms the subject matter of a companion application.

In making bacterial analysis of air the collecting film is preferably formed centrifugally out of a gelatinous cultural substance, which at normal 55 temperature is a jelly-like mass but which becomes liquid when hot, such for example as the well known agar medium; but in other analyses of air a collector sheet of celluloid or other suitable material may be inserted as a removable lining 60 for the container and this has the advantage of ready removal from the revolving or centrifugal container so that the centrifugally extracted particles distributed over its surface may be easily subjected to microscopic or other examination and 65 testing or counting after the lining has been removed. When the agar or like compound is used for the collecting medium or film, as above described, it is unnecessary to remove it from the glass test tube because the cultural development 70 can be seen through the transparent wall of the

test tube or container and the count of cultural centers can be easily made from the outside, but this form of collector is not so well adapted to microscopic or chemical analysis of the particles and for such and similar purposes it is preferred 5 to use a removable lining film inside the centrifugal container by reason of the greater accessibility afforded. Indeed, the test tube itself without any lining could be used as a collector of the centrifugally extracted particles since those 10 particles are expelled with sufficient force at high speed to remain in fixed position on the inside surface of the container, and bacteria so deposited 15 could be treated later with a cultural medium to cause their development for further study. It will therefore be understood that the term "collector" is used herein to apply equally to the receptacle or container whether it be provided with a lining film or not, and whether such lining film be formed by centrifugal action as above described or be formed by an insertable and removable sheet or film of material, so long as there is provided a collecting surface directly exposed to the moving column of air and serving as a means for collecting or retaining the particles 20 centrifugally expelled upon it from the air. Since this arrangement provides for the lengthwise flow of a thin column of air, which receives its revolving motion from the revolving container, it will be seen that there will be an acceleration of revolution 25 of the air as it moves toward the outlet end of the container-collector, thus causing a selective distribution of the particles along successive areas of the collector, the heavier particles being expelled first and the progressively lighter 30 particles being deposited in order of their mass.

What I claim is:

1. An apparatus for air analysis embracing a supporting standard, a laterally projecting bracket slidably mounted thereon, a vertical air 40 intake tube secured in said bracket for support, a bearing head carrying an exhaust fan revolvably mounted around said tube, a tubular casing having its upper end seated in said bearing head, a driving element connected with said casing, said 45 air intake tube projecting down inside said tubular casing, an intermediate tube secured in said head and extending downward between said casing and said air intake tube and a removable liquid receptacle inserted between the casing and 50 said intermediate tube.

2. An apparatus for air analysis embracing an upright standard, a laterally extending bracket projecting from said standard, an air intake tube mounted in said standard to project downwardly 55 therefrom, a radial bearing mounted on said air tube below the bracket, a revolvable head mounted on said bearing concentrically of said air tube, said head being provided with vanes for producing circulation of air and having concentric spaced 60 bored recesses for receiving concentric tubes arranged concentrically around said air intake tube and providing an annular space for the reception of a tubular film container, a supporting and driving element detachably secured to the outside 65 tube and forming a bottom support for a liquid container inserted between the two spaced concentric tubes.
